UNITED STATES PATENT OFFICE.

LAURENT MORIN, OF MAISONNEUVE, CANADA.

WOODWORKING-MACHINE.

SPECIFICATION forming part of Letters Patent No. 726,968, dated May 5, 1903.

Application filed May 31, 1901. Serial No. 62,454. (No model.)

To all whom it may concern.

Be it known that I, LAURENT MORIN, a subject of His Majesty the King of Great Britain, residing at Maisonneuve, county of Hochelaga, Province of Quebec, Canada, have invented certain new and useful Improvements in Woodworking-Machines; and I do hereby declare that the following is a full, clear, and exact description of the invention, such as will enable others skilled in the art to which it appertains to make and use the same.

My invention relates to improvements in combination woodworking-machines; and one object in view is the provision of a power-driven machine by which a variety of operations may be performed on one and the same machine under the condition that a change (which may be easily and quickly effected) in the position of one or more working devices shall be performed.

A further object is to provide a primary tool-shaft with means for adjustably supporting it in place, whereby said shaft may be used in connection with planing, sawing, boring, or pattern-molding mechanisms.

A further object is to equip the machine with an adjustable work-bed and feed mechanism for the purpose of feeding the stock or material to the planing or dressing mechanism from above or below the same to allow adjustment of said bed while retaining its necessary horizontal alignment and to apply or exert pressure on the material during the operation of advancing the latter.

A further object is to allow certain of the tables to be used in connection with the sawing and boring mechanisms and to secure adjustment of the main table so as to clear the primary tool-shaft when the position of the latter is changed and to permit of sawing or cutting the work at an angle.

With these ends in view the invention consists in the combination, construction, and arrangement of parts, which will be herein-after fully described and claimed.

In the drawings hereto annexed, forming a part of this specification, Figure 1 is a side elevation of my combination woodworking-machine. Fig. 2 is a vertical cross-section on the line 2 2 of Fig. 1 looking in the direction of the arrow. Fig. 3 is a vertical longitudinal section on the line 3 3 of Fig. 2 look-

ing in the direction of the arrow. Fig. 4 is another longitudinal sectional view on the line 4 4 of Fig. 2 and looking in the direction 55 of the arrow. Fig. 5 is a vertical cross-section on the line 5 5 of Fig. 3 looking in the direction of the arrow and showing a portion of the machine broken away. Fig. 6 is another vertical cross-section through a part of 60 the machine in the plane of the dotted line 6 6 on Fig. 3 and looking in the direction of the arrow. Fig. 7 is a vertical detail cross-section through a front part of the machine in the plane indicated by the dotted line 7 7 on Fig. 65 1 and looking in the direction of the arrow. Fig. 8 is an enlarged vertical section through a part of the machine adjacent to the revolute cutter-head on the primary tool-shaft when the latter is adjusted to serve as a 70 means for planing or dressing the stock, said view showing a yieldable counterpoised shield, which is adapted to serve as a chip-breaker. Fig. 9 is a transverse section through a part of the machine, illustrating 75 the primary tool-shaft adjusted to a vertical position and equipped with a cutter-head adapted to operate on the work for making moldings or cutting grooves. Fig. 10 is a detail sectional plan view, the plane of the section being indicated by the dotted line 10 10 on Fig. 9. Fig. 11 is a partial end view of the machine, representing the primary tool-shaft adapted for the actuation of a boring-tool, which is adapted to operate on work 85 placed upon the shiftable auxiliary table of the machine. Fig. 12 is a detail view illustrating the main table equipped with means for supporting the same in inclined positions. Fig. 13 is a plan view of one of the tables 90 equipped with an adjustable metallic plate and adapted to be used in connection with a horizontal cutter-head. Fig. 14 is a cross-section through said table on the line 14 14 of Fig. 13. Fig. 15 is a detail perspective 95 view of the counterpoised shield, which may be used under some conditions and in operative relation to a horizontal cutter-head, as in Fig. 8. Fig. 16 is an enlarged detail sectional view of the boring-head. Fig. 17 is a 100 detail vertical section through a removable bearing adapted to support one extremity of the primary tool-shaft when the latter is adjusted to work in a horizontal position. Fig.

18 is a detail fragmentary view of one of the means employed to hold the horizontal work-bed in a fixed position, the same having a section on the line 18 18 of Fig. 1. Fig. 19 is 5 a detail cross-section on the line 19 19 of Fig. 1, illustrating the means for clamping the adjustable rear table in position.

The same numerals of reference denote like parts in each of the several figures of the 10 drawings.

The main frame 5 of the machine may be divided into a right-hand portion 5^a and a left-hand portion 5^b, viewed in Figs. 2, 5, 6, 15 7, and 9, each portion adapted to support some of the operating mechanisms, which will be hereinafter described. It will of course be understood that the detailed construction of this framework may be varied within wide limits, and the form of said framework here- 20 in shown being only one embodiment of the means by which the operating mechanisms are sustained in positions for service.

6 designates a horizontal work-bed, which is arranged longitudinally of the left-hand 25 portion 5^b of the framework, within the latter. This horizontal framework lies between pairs of slotted standards 7 7^a 7^b and one or more other frame-standards 7^c, the slots in the standards 7 7^a 7^b being indicated at 8 8^a 8^b. 30 A series of transverse rods 9 9^a 9^b are secured in the bed in positions to extend through the slots in the series of standards, each rod being provided at one end with a head 10 (see Figs. 4 and 17) and having its other end 35 threaded for the reception of the hand-wheel 11, a washer 10^a being interposed between the head of the rod and the slotted standard, whereby the rods may be tightly clamped against the posts of the framework, so as to 40 solidly support the work-bed in its adjusted position.

I will now proceed to describe the means for adjusting the work-bed in a vertical direction while maintaining the same in a horizontal position at all points of its movement, reference being had to Figs. 1, 2, 3, 5, 6, and 7, inclusive. At the front rear end of the left-hand portion 5^b of the frame are provided the stationary frame-rails 13 13^a, each having a vertical passage 14 and supporting one of the fixed plates or nuts 15 15^a, each of the latter being secured firmly to the cross-rail in position for the female threaded opening in the nut to lie in the vertical plane of the 55 passage 14 of the cross-rail. (See Fig. 3.) With the nuts (which are maintained in stationary positions by the cross-rails) engage the vertical screw-spindles 16 16^a, the same passing through the passages 14 in the cross- 60 rails and arranged for the threads of said spindles to engage with the threads of the nuts. The upper ends of the spindles bear against thrust-plates 17, which are provided on the under side of the work-head near the 65 end portions thereof, and these spindles are adapted to freely rotate in order to raise or lower them and impart a corresponding ad-

justment to the horizontal bed. The screw-spindle 16 at the front portion of the machine is equipped with a bevel gear-pinion 18, the 70 same arranged to have intermeshing engagement with beveled gear-teeth 19^a on a compound gear 19, the latter having an annular series of spur-gear teeth 19^b, whereby the compound gear 19 is provided with two series 75 of gear-teeth, which are formed by the series of beveled teeth 19^a and by the series of straight spur-teeth 19^b. This compound gear is secured firmly to the end portion of the bed-adjusting shaft 20, the latter arranged in 80 a horizontal position underneath the bed and extending longitudinally thereof, (see Fig. 3,) said shaft being journaled near its end portions in hangers 21, which are secured firmly to the under side of the bed, whereby the 85 shaft 20 is journaled on the bed, so as to be carried thereby in its up-and-down movements within the frame. The rear portion of this bed-adjusting shaft is provided with a bevel-gear 22, which is arranged to have 90 intermeshing engagement with a beveled gear 23, the latter being secured fast to the screw-spindle 16^a at the rear of the machine. By reference to Fig. 7 it will be seen that the spur-gear teeth 19^b of the compound gear 19 95 on the bed-adjusting shaft 20 have intermeshing engagement with a spur gear-pinion 25, that is secured firmly to a short horizontal shaft 26, the latter being suitably journaled in a bearing 27 on the under side of the 100 bed 6 at the front portion thereof, said hand-shaft being provided with a hand-wheel 28, which is adapted to be rotated by the hand of the operator. This hand-shaft 26 provides the means whereby the shaft 20 may be rotated with ease and convenience, and said shaft 20 through the described chain of gearing is adapted to simultaneously rotate the screw-spindles 16 16^a, so as to raise or lower 105 them in the nuts 15 15^a, whereby the horizontal bed may be raised or lowered and be retained in a horizontal position at all points of its adjustment. It will be observed that it is necessary to loosen the series of hand-wheels 11 previous to rotating the hand-shaft 110 for the adjustment of the work-bed, that the series of rods 9 9^a 9^b are adapted to travel in the slots of the standards on the adjustment of the bed, so as to limit the latter to vertical movement, and after the bed has been 115 given the desired adjustment these hand-wheels 11 may be tightened in order to clamp the rods and the bed firmly in their adjusted positions. This work-bed carries a series of 120 idle feed-rolls 29. (Shown by Fig. 3 as consisting of two rolls arranged to protrude through suitable slots in a face-plate 30, although the number of rolls is not material.) Each roll is journaled in a pair of plates 31, which is let into recesses in the sides of the 125 bed, as shown by Figs. 5 and 6, and with these bearings engage the upper ends of vertical adjusting-screws 32, the latter being 130 suitably mounted in the bed and engaging

with the lower ends of the roller-bearings, whereby the roller may be raised or lowered, as desired. The plates 31 for the roller shown by Fig. 6 are provided with longitudinal slots 33, through which pass the clamping-bolts 34, whereby the roller-bearings may be clamped laterally against the edges of the bed, and the adjusting-screws 32 are made to assist in holding the bearings in their adjusted positions.

35 designates an idle upper feed-roll which is arranged practically in the same plane as the rear lower feed-roll 29 in order that it may coöperate therewith; but this upper roll 35 is held under yielding pressure in order that it may have normally a tendency to move toward the lower idle feed-roll. The roll 35 has its trunnions slidably fitted in the slots 36, which are provided in the stationary bearing-plates 37, that are fastened to the left-hand portion of the framework 5^b, (see Fig. 6,) and with the roll-trunnions are engaged the hooked-shaped upper ends of the tension-rods 38, the latter being provided in pairs on opposite sides of the framework-section 5^b, as shown by Fig. 6, and the lower ends of said tension-rods being engaged with the pairs of springs 39, which are connected by the hook-bolts 40 to the bottom portion of the framework.

41 designates a driven feed-roll, the same being arranged in the same horizontal plane as the upper idle feed-roll 35 and disposed substantially in the vertical plane of the front lower roll 29. (See Figs. 3 and 5.) This driven roll 41 consists of a shaft 42 and a plurality of disk-like members 43, the latter being of corresponding diameter, threaded on the shaft, so as to occupy parallel relation, and provided with roughened peripheries, with a view to producing a working surface on said driven feed-roll which will properly engage with the lumber or other piece of wood desired to be planed. One end portion of the roll-shaft 42 is fitted loosely in a slot 44 of one of the pair of bearing-plates 45. Through the slot in the other bearing-plate of the pair passes the other end portion of the roll-shaft, as shown by Fig. 5. With this shaft of the driven feed-roll engage the upper hooked ends of the tension-rods 46, the lower ends of which are engaged by the springs 47, that are fastened to the frame, whereby the rods and springs draw the roll 41 downwardly toward the front lower roll 29. The inner portion of the feed-roll shaft passes through a slot 48, which is provided in one of the horizontal rails of the frame, (see Fig. 5,) and to this end of the shaft is secured a spur gear-wheel 49. (See Figs. 4 and 5 and dotted lines in Fig. 3.) This gear-wheel has intermeshing engagement with an intermediate idler-gear 50, which is loosely mounted on a stub-axle 52, that is secured to the frame within the section 5^a thereof, and said idler-gear 50 furthermore has intermeshing engagement with a gear-pinion 53 on the hub of a large master-

gear 54, the latter being mounted on another stub-axle 55, secured to a stationary post 56, forming a part of the frame. This master-gear has intermeshing engagement with a gear-pinion 57, which is fast with the hub of a belt-pulley 58, the latter being journaled on a stub-axle 59, also attached to the post 56. All the before-described gearing constitutes a train of reducing-gearing from the belt-wheel to the feed-roll shaft 42, said parts arranged and adapted to propel the feed-roll 41 in the proper direction and to impart a very slow speed thereto as compared with the speed of the belt-wheel 58. An endless driving-belt 60 encompasses the belt pulley or wheel and is itself driven from the shaft of a motor or from a counter-shaft, (not shown,) and with this driving-belt engages a tight-ener-pulley 61, the latter being journaled on a treadle-lever 62, which is fulcrumed to the frame, as at 63, all as clearly shown by Fig. 4, thus making provision for readily throwing the train of feed-gearing into and out of service by simply adjusting the treadle-lever 62.

The horizontal bed and the two series of feed-rolls heretofore described constitute one of the means for presenting work to a primary tool-shaft, which series of work-presenting means are employed in a convertible wood-working-machine contemplated by this invention. My machine also contemplates the employment of a single tool-shaft, which is operatively supported by shiftable devices arranged to present the tool-shaft in horizontal or vertical positions, and with this single tool-shaft I have associated a series of revolvable tools, one or more of which are applied to the shaft in either of its adjusted positions. This primary tool-shaft is indicated by the numeral 65, the same being journaled at points intermediate of its length in proper bearings 66 67, which are provided on the shiftable bed 68, said bearings being arranged at the end portions of the bed, so as to leave an intermediate space on the shaft sufficient to accommodate the wide belt-pulley 69, the latter having a rim 69^a at one end, whereby the belt-pulley is secured to the shaft about the middle thereof, and it is adapted to operate said shaft when adjusted to assume either the horizontal or vertical positions. (Shown more clearly by Figs. 2 and 9.) The end portions of the tool-shaft are exteriorly threaded, as indicated at 70 71 in Fig. 9, whereby said shaft is adapted to receive the rotary tools. I have herein shown the machine equipped with a planer-head, a molding cutter-head, a circular saw, and a boring-tool head; but I would have it understood that these heads are used interchangeably with the end portions of the tool-shaft and according to the position which the latter may assume in the machine.

The right-hand portion 5^a of the frame is provided near the middle portion of the machine with a wide vertical frame-plate 72, the latter having the vertical flanges 73, through

which are bolted the plates 74, said parts arranged, as shown by Figs. 9 and 10, to form the guideways 75 for a vertically-slidable carriage 76. This carriage 76 is arranged to slide 5 up or down in the ways on the stationary frame-plate and any lost motion of the carriage is taken up by the set-screws 77, the latter being screwed into suitable openings provided in the flange of the frame-plate and 10 arranged in a position to engage with an edge of the carriage. (See Fig. 10.)

The tool-shaft bed 68 is connected adjustably or shiftably to the vertically-slidable carriage 76, said bed being movable with the 15 carriage when the latter is raised or lowered and being also capable of a shiftable adjustment on the carriage independently of any motion thereof. The bed is provided at its middle portion with a transverse slot 78, (see Fig. 5,) in which slot is snugly fitted the beveled head of a bolt 79, (see Fig. 10,) said bolt passing through an opening 80 in the upper portion of the carriage 76 and receiving a clamp-nut 81 at its rear end. This bed is 20 shiftable on the carriage by moving it on the axis afforded by the bolt 79, and it will be evident that the bed and the tool-shaft may be turned to assume the horizontal position shown more clearly by Figs. 2 and 11, or said 25 parts may be turned to the vertical position shown by Fig. 9. When the bed 68 and the tool-shaft are in their horizontal positions, the bed is held securely in place by suitable bolts, which are inserted from the rear through 30 apertures 82, provided in the slideable carriage 76, said bolts entering suitable tapped openings in the tool-shaft bed 68. The left-hand end of the primary tool-shaft 65 when the latter and the bed are in the horizontal positions of Fig. 2 is adapted to be partially supported in a shaft-bearing 83, the latter being provided at the upper portion of a bearing-plate 84, which is secured by one or more bolts 85 to the framework portion 5^b, and this 35 bearing-plate 84 and its associated parts are adapted to be entirely removed from the frame in order to release the tool-shaft 65 and permit it to be adjusted with its bed to the vertical position. 40

The bed 68 is of a length somewhat less than the width of the slideable carriage in order that it may lie across the latter when in the horizontal position indicated by Fig. 2; but when the bed is shifted so that it assumes 45 the vertical position of Fig. 9 it is adapted to be held in place by means of bolts (not shown) inserted from the rear through openings 86, which are provided in the lower portion of the slideable carriage 76, as shown by Fig. 2, 50 said bolts being received in suitable tapped openings provided in the bed. It will be observed that the bed may be turned around on the axis afforded by the bolt 79, that the bed is adapted to be moved across the carriage 55 because the bolt 79 is received within the slot 78, and that the bed may be held securely in either of its adjusted positions by suitable

fasteners, which engage with the carriage and with the bed.

87 designates a driving-belt which is operatively fitted to the pulley 69 of the tool-shaft. This belt is adapted to drive the tool-shaft in either of its adjusted positions, because it may be fitted to the pulley 69. In Fig. 4 this belt is shown as encompassing the pulley 75 when the shaft is in its horizontal position; but said belt is adapted to occupy a like relation to the pulley when the tool-shaft is moved to an upright position. The belt 87 may be propelled from a motor or a line shaft, 8c and it serves to drive the tool-shaft independently of the means for propelling the feed mechanism.

Any suitable means may be provided for adjusting the carriage 76 and its contained parts; but in the drawings I have shown a vertical carriage-adjusting shaft 88, having a swiveled connection at 89 with the lower portion of the carriage. (See Figs. 2 and 4.) This shaft is externally screw-threaded for a 90 part of its length in order that it may have engagement with a stationary feed-nut 90, which is provided by a lip or flange on the lower edge of the vertical frame-plate 72, the lower portion of said carriage-adjusting shaft 95 88 being confined in a suitable bearing 91 at the bottom of the framework. A beveled gear-pinion 92 is keyed or splined to the lower portion of this threaded shaft 88 and is arranged to have intermeshing engagement with 100 a similar pinion 93 on a hand-operated shaft 94, the latter being journaled in bearings at the lower portion of the machine, as shown by Fig. 4, and provided with a hand-wheel 95, whereby the shaft 88 may be rotated for 105 the purpose of raising or lowering the carriage 76.

When the tool-shaft 65 is adjusted to its horizontal position, its left-hand end portion is adapted to sustain and operate a cutter-head 96 as one of the revoluble tools, while the right-hand portion of the shaft has a circular saw 97 clamped thereto in any of the usual ways familiar to those skilled in the art. This cutter-head and the saw are removable from the shaft, so that other revoluble tools may be secured thereto—such, for example, as the molding cutter-head 98, which is represented by Fig. 9. This last-mentioned cutter-head has two large members 98^a clamped thereon and adapted to support the bits 98^b, although the head members 98^a and the bits may be detached, so that provision may be made for the attachment of the smaller head members 98^c, which are recessed 125 to receive certain other similar bits. (Not shown.) It is evident that any desired size and shape of bits may be clamped to the threaded end 71 of the tool-shaft when in its vertical position, as shown by Fig. 9, thus enabling the cutter-head 98 to perform a variety of work on the stock, which may rest upon the main table 99, the latter arranged to direct the stock to the cutter-head 98. This

cutter-head 98 is removably secured to the end 71 of the tool-shaft, so that it may be interchanged with the cutter-head 96, whereby the two cutter-heads are interchangeable with the same end of the shaft. The cutter-head 96 5 may be of any suitable construction, so that removable blades 96^a may be secured to the several faces of said cutter-head 96. (See Figs. 3 and 8.) The cutter-head 96 is operatively related to the work-bed 6 and lies between the feed-rolls 35 41, whereby the cutter-head is adapted to serve as the means for planing the stock which may rest upon the bed 6 and is adapted to be advanced to the cutter-head by the feed-rolls. 15

The main table 99 extends the full length of the machine and is arranged to cover the right-hand portion 5^a of the framework. (See Figs. 2 and 9.) Said table has hinged connection at one edge with the framework, as indicated at 100 in the detailed view, Fig. 12, whereby the other free edge of the table, which lies next to the left-hand portion 5^b of the framework, may be raised to the position indicated by dotted lines in Fig. 12, thus permitting the main table to be lifted out of the way when it is desired to adjust the bed 68 and the tool-shaft supported thereon. The table is furthermore provided with a large central opening 101 and with a metallic plate 102, the latter being set in the table flush with the upper surface thereof, and likewise provided with a central opening 103, (see Fig. 9,) through which openings 101 and 103 is 25 adapted to pass the upper portion of the tool-shaft and the lower portion of the molding cutter-head 98. It is evident that the main table may be provided with any of the usual guides or other accessories for the purpose of 30 holding or feeding the work properly to the vertical cutter-head 98. The main table 99 is furthermore provided with the links 104, one of which is pivoted, as at 105, to the outer corners of the table at the free edge thereof, 35 thus disposing the links at the ends of the table and the framework, and these links are arranged to slide freely in the clips 106, which are fastened to the ends of the framework portion 5^a, each clip supporting a clamping- 40 screw 107, that is arranged to bind against the link and to maintain the pair of links and the table in their adjusted positions. The table 99 is thus adapted to be held at an angle, as indicated by dotted lines in Fig. 12, 45 for the purpose of feeding the stock to the vertical cutter-head or to the circular saw when it is desired to have either of said rotary tools operate on the stock while in its inclined position. 50

60 108 designates the front table, which is secured in the upper portion 5^b of the framework and at the front or right-hand end of the latter. (See Fig. 3.) This table is secured in place so that preferably it is non-adjustable, and upon the table rests a metallic plate 109, the latter having the depending flanges 110, that are fitted in recesses of the table, as

shown by Fig. 5, said metallic plate terminating at its inner edge near the cutter-head 96 and preferably in a plane above the latter 70 when in its operative relation to the work-bed.

111 designates the upper rear table, which is arranged over the portion 5^b of the framework at the upper portion thereof, and said rear table is provided with a metallic plate 75 112, having the depending flanges 113, fitted in recesses of the rear table 111, as shown by Figs. 3 and 6. Unlike the front table 108 this rear table and its plate are supported adjustably on the framework, so that the 80 plate may be raised or lowered with relation to the cutter-head for the purpose of presenting the work to regulate the depth of the cut. This is attained by the provision of inclined slots 114 in the table 111, and through these 85 slots pass the fastening-rods 115, the latter extending also through the framework 5^b and provided at one end with a head and at its other end with a series of screw-threads, so that a clamping-wheel 116 may be screwed on 90 the rods. The table 111 has a nut 117 depending from the middle portion thereof, and in this nut is screwed the threaded portion of a horizontal adjusting-shaft 118. (See Fig. 3.) Said shaft has a swiveled connection at 119 with the rear portion of the framework, and the rear projecting end of the shaft is provided with a hand-wheel 120, whereby the shaft may be rotated for the purpose of giving endwise movement to the rear table, 100 the inclined slotted portions of which are adapted to travel on the rods 115, so as to raise or lower the table and its plate 112 with relation to the horizontal plane of the cutter-head 96. Of course the clamping-wheels 116 105 should be released when it is desired to adjust the table by manipulating the shaft 118; but these wheels may be retightened, so as to hold the rear table and its plate firmly in their adjusted positions. 110

121 designates a gage which is arranged to overhang the adjacent portions of the tables 108 111 and be disposed above and adjacent to the inner edge of the cutter-head 96, thus making provision for guiding the work to 115 the cutter-head when it is passed over the rear table 111 of the cutter-head and thence over to the front table 108. The gage is held adjustably in place by having the rearwardly-extending arms 122, one of which is shown 120 by Fig. 5, each clamped upon the main table 99 by a screw 122^a. Each table 108 or 111 has its metallic plate clamped adjustably thereto in the manner shown by Figs. 13 and 14, thus making provision for the adjustment of the 125 metallic plate with reference to the vertical axis of the cutter-head 96 independently of the table, whereby the two metallic plates may be moved toward or away from the cutter-head without changing the position of either table. This is accomplished by the provision of slots 123 in each plate, and through each slot passes a clamping-screw 124, which is embedded in the table and has its headed end 130

disposed in the slot so as to be flush with the top face of the plate. (See Fig. 14.)

In connection with the circular saw 97 I employ an auxiliary slidable table 125, (see Fig. 2,) said table being of a length equal to that of the machine and arranged at one side of the main table, preferably in the same horizontal plane therewith, although this auxiliary table is adapted to be moved from the position shown by Fig. 2 and placed in the position shown by Fig. 11. The auxiliary table is supported by a table-frame 126, the same having at its end portions the inwardly-extending arms 127, the latter being slidably received in the loops 128, which are fastened to the right-hand portion 5^a of the framework, (see Fig. 4,) whereby the table-frame 126 may be moved outwardly from the frame 5, so as to withdraw the arms 127 from the loops 128. The auxiliary table is provided on its under side with the guide-plates 129, which are arranged to have underlapping relation to the guide-plates 130, which are fastened on the frame 126 so as to extend longitudinally thereof, the operative relation of the two sets of guide-plates being clearly indicated by Fig. 2. The guide-plates 129 extend lengthwise of the table 125, so that they will embrace the guide-plates 130 in a manner to hold the auxiliary table against crosswise displacement and at the same time permit said auxiliary table to be adjusted in an endwise direction along the frame 126 and close to the position of the circular saw 97. This auxiliary table is thus adapted to serve as a means for feeding a log or other piece of stock to the circular saw, and said auxiliary table may be equipped with any of the usual appliances for holding the log and adjusting the same.

131 designates a saw-gage which is supported on the main table 99 close to the position of the circular saw, and this gage is held adjustably in place by arms, one of which is indicated at 132 in Fig. 2, said arm being fastened adjustably to the table 99 by a clamping-screw 133.

The auxiliary table may be withdrawn from the position shown by Fig. 2 and arranged in the position shown by Fig. 11, wherein the table occupies a horizontal position below the outer right-hand-threaded portion 70 of the tool-shaft. The table is supported in its underneath position by having its arms 127 fitting in the spaces or ways formed by and between pairs of bars 134, one pair of which are secured to each end of the right-hand portion 5^a of the frame, as indicated by Fig. 11. The bars 127 may be slid to any desired extent into the ways formed by the stationary bars 134, so as to support the auxiliary table 125 and permit it to be adjusted in a horizontal direction toward and from the frame 5, whereby the work supported by the auxiliary table may be forced up to the boring-tool 135. This tool has its shank fitted in a socket 136 of a boring-head 137, so as to be held therein by the clamping-screw 138, and this boring-

head is provided with an internally-threaded socket 139, whereby it may be screwed upon the threaded extremity 70 of the tool-shaft 70 when the latter is adjusted to the horizontal position shown by Fig. 11.

When the machine is adjusted for planing work on the bed 6 by raising the latter to the close relation to the cutter-head 96 shown by Fig. 8 and by removing the table 108 from the front portion of the framework, I employ the yieldable chip-breaker 140. (See Figs. 8 and 15.) This chip-breaker is curved in cross-section and tapered to an edge, as at 141, and it is provided with the curved arms 142, the same arranged parallel and having the eyes 143, through which may be passed the pivotal bolts 144, that serve to pivotally connect the chip-breaker to the frame at points above the horizontal plane of the cutter-head 96 and in rear of the latter. The chip-breaker is provided with an outwardly-extending stem 145, on which is shiftably fitted a weight 146, that is clamped adjustably on the stem by a set-screw 147, and this weight is arranged to normally press the pivoted chip-breaker toward the bed, whereby the curved device 140 is arranged to intercept the chips and slivers which are cut from the log by the rotary action of the cutter-head 96. The chip-breaker is free to yield or give in an upward direction away from the bed and laterally with respect to the cutter-head, because it is pivoted in the manner shown and described; but the weight 146 normally holds the chip-breaker to its operative position. The downward movement of the chip-breaker, however, is limited by the provision of a set-screw 148, which is screwed into a threaded opening 105 of a lug 149, that is provided on one edge of the chip-breaker, (see Fig. 15,) and this screw is arranged to rest upon an ear 150 of a stop-plate 151, the latter being secured adjustably to the upper portion 5^b of the framework and disposed in the path of the set-screw 148, which is carried by the chip-breaker. The bolts 144 may easily be withdrawn from the frame, so as to permit removal of the chip-breaker, and thus the entire device may be applied to the machine or removed therefrom, according as it is desired to plane the work by feeding it to the cutter-head and the bed and through the agency of a feed mechanism.

This being the general and detailed construction of my machine, the operation may be described briefly as follows: With the bed 68 adjusted to the horizontal position (shown by Figs. 2, 3, 4, 8, and 11) the tool-shaft 65 may be used for either of the following purposes, to wit: The head 96 is adapted to dress the stock or material which may be fed from the rear to the front on the plate 112 of the rear table, thus presenting the material in the path of the cutter-head 96, at the upper portion thereof, and allowing the material to pass to and upon the plate 109 of the front table 108. The bed 6 may be adjusted in operative relation to the cutter-head for the pur-

pose of planing or otherwise treating a log or other piece of timber adapted to be fed along the bed by the feed mechanism, the driven roll 41 of which is propelled by the train of reducing-gearing. The circular saw 97 may be propelled by the shaft 65 and adapted to operate on a log which is advanced to the saw by sliding the auxiliary table 125 on its supporting-frame 126, or the boring-head 137 may be applied to the shaft 65 in lieu of the circular saw, which adaptation of the machine requires the table 125 to be supported below the boring-tool in the position shown by Fig. 11. The cutter-head 96 and the tool at the other end of the tool-shaft 65 may be dismounted, after which the table 99 may be raised, the bed 68 turned on the pivot afforded by the bolt 79, and the threaded end 71 of said shaft 65 may be passed through the openings 101 103 in the table 99 and the plate 102 thereon. This allows the cutter-head 98 to be attached to the upper end of the shaft 65, and the machine may now be operated to produce a desired pattern of molding or for tonguing and grooving purposes.

In using the machine for planing lumber I prefer to dismount the front table 108 and to pivotally connect the chip-breaker 140 to the frame in a position to overhang the cutter-head 96, as shown by Fig. 8.

From the foregoing description, taken in connection with the drawings, it will be seen that I have provided a convertible machine which may be used for the performance of a variety of work on wood, and, furthermore, it is evident that the change in the machine from one of the revoluble tools to another may be easily and quickly performed, whereby a machine-shop may be equipped with one single machine which will satisfactorily perform the work heretofore required to be done by a number of different pieces of expensive machinery.

Changes within the scope of the appended claims may be made in the form and proportion of some of the parts while their essential features are retained and the spirit of the invention is embodied. Hence I do not desire to be limited to the precise form of all the parts as shown, reserving the right to vary therefrom.

Having thus described my invention, what I claim as new is—

1. In a convertible woodworking-machine, a tool-shaft bed, a plane-faced support on which said tool-shaft bed is adjustably clamped parallel to the face thereof, means for clamping said bed in either vertical or horizontal position on said support, and a tool-shaft journaled in and adjustable with said bed and having a tool-mandrel formed on each end thereof, combined with work-presenting means, a cutter-head mounted on one of said mandrels, and means for driving the shaft.

2. In a convertible woodworking-machine, the combination of a vertically-slidable car-

riage having one side planed flat, a tool-shaft bed having an adjustable connection with said carriage on the planed side thereof and adapted to be clamped parallel to said planed side and in vertical or horizontal positions thereon, a tool-shaft mounted on the bed, a series of revoluble tools adapted to be used interchangeably with the shaft, and means for presenting work to said revoluble tools, substantially as described.

3. In a convertible woodworking-machine, the combination of a frame-plate provided with vertical guideways, a vertically-slidable carriage confined in said guideways and having one side faced, a removable tool-shaft bed clamped to the faced side of the carriage and adapted to be adjusted in either vertical or horizontal positions thereon, a tool-shaft journaled in the bed and adapted for the attachment of either of a series of revoluble tools, means for driving said shaft, and means for presenting work to the tool both in its horizontal and vertical positions.

4. In a convertible woodworking-machine, the combination of a tool-shaft bed, a tool-shaft journaled therein and adapted for the application of either of a series of revoluble tools on its overhung end, means for adjusting said bed and its shaft into either a horizontal or a vertical position for service, a bearing carried by the frame arranged to receive and support the overhung end of the tool-shaft beyond the tool when in its horizontal position, means for propelling said tool-shaft, and means for presenting work to the revoluble tool in either position of the shaft, substantially as described.

5. In a convertible woodworking-machine, the combination of a vertical frame-plate, a carriage slidably confined thereon, a threaded adjusting-shaft working in a fixed bearing-nut and having a swiveled connection with said carriage, means for rotating said shaft, a bed mounted on the carriage to travel therewith and capable of an adjustment shiftable from vertical to horizontal position thereon, a tool-shaft journaled in the bed and adapted for the application of a series of revoluble tools, and means for presenting work to one of said tools in either position of the shaft, substantially as described.

6. A convertible woodworking-machine comprising a suitable framework, a vertically-slidable carriage thereon having a planed face, a vertically and horizontally adjustable bed adapted to be clamped to the planed face of said carriage and provided with a tool-shaft, a work-bed arranged longitudinally within the frame and occupying an operative relation to a revoluble tool on said tool-shaft in one position of the latter, a feed mechanism also occupying an operative relation to the tool-shaft and to the bed, and means for propelling the tool-shaft, substantially as described.

7. A convertible woodworking-machine comprising a suitable framework, a carriage

vertically slidable therein, a bed mounted shiftably on the side of the carriage and adapted to be clamped thereto and supporting a tool-shaft, a work-bed slidably confined in said framework and carrying feed-rolls disposed in coöperative relation to a revolute tool on the tool-shaft in one position of the latter, a longitudinal horizontal adjusting-shaft journaled on the work-bed, a plurality of bevel gear-pinions carried on said adjusting-shaft, a plurality of vertical screw-spindles supporting the bed and working in fixed bearing-nuts, and bevel-pinions carried by the respective spindles and meshing with said first-mentioned pinions, whereby the work-bed is adapted to be raised or lowered while maintaining a horizontal position at all points of its adjustment.

8. A convertible woodworking - machine comprising a framework, a slidable carriage, a bed shiftably supported on the carriage and having a tool-shaft adapted for the application of a series of tools, a work-bed having means for vertically adjusting the same with relation to a tool on the tool-shaft, feed-rolls mounted on said work-bed, a pair of upper feed-rolls disposed on opposite sides of the tool-shaft and having vertically-slidable bearings, a hooked rod engaging the upper side of each bearing, a spring attached to the lower end of each rod and to a stationary part of the frame, and reduction-gearing for driving said last-mentioned feed-rolls, substantially as described.

9. A convertible woodworking - machine comprising a suitable framework, a main table hinged thereto and having means for fastening the same when adjusted at an inclined angle to said framework, a carriage mounted to slide vertically in the framework and having a planed lateral face, a bed provided with a tool-shaft and shiftably mounted on the planed face of the carriage for adjustment to a vertical position, and a series of revolute tools applicable to said tool-shaft, substantially as described.

10. A convertible woodworking - machine comprising a suitable framework, a carriage slidable thereon, a bed provided with a tool-shaft and shiftable on the carriage to assume either vertical or horizontal positions, a series of revolute tools applicable to said tool-shaft, a table-frame having detachable connection with the framework, and a table slidably connected to the table-frame and arranged in coöperative relation to one of the series of tools on said tool-shaft, substantially as described.

11. A convertible woodworking - machine comprising a suitable framework, a shiftable bed provided with a tool-shaft and adjustable for said shaft to assume either a vertical or horizontal position, a series of revolute tools applicable interchangeably to said tool-shaft, an auxiliary slidable table, and means substantially as described whereby said table

may be supported on the framework above or below the horizontal position of the tool-shaft and in coöperative relation to one of two revolute tools operable by said tool-shaft.

12. A convertible woodworking - machine comprising a suitable framework, a bed provided with a tool-shaft, a series of revolute tools applicable interchangeably to said tool-shaft, a horizontal work-bed below said shaft and having means for adjusting the same into coöperative relation to one of said revolute tools on the tool-shaft, an upper stationary table having an adjustable plate disposed at one side of said revolute tool, an adjustable table arranged on the opposite side of the revolute tool and provided with a feed-plate which is adjustable independently of the table, and means for adjusting said table, substantially as described.

13. A convertible woodworking - machine comprising a suitable framework, a bed provided with a tool-shaft, a series of revolute tools applicable interchangeably to said tool-shaft, a horizontal work-bed below said shaft and having means for adjusting the same into coöperative relation to one of said revolute tools, a non-adjustable front table removably secured to the framework above the work-bed and at one side of the revolute tool, and an adjustable rear table disposed on the other side of the revolute tool and above the work-bed, substantially as described.

14. A universal woodworking - machine comprising a frame having a vertical faced plate, a tool-shaft bed adapted to be clamped in various positions on the face of said plate, and a tool-shaft mounted in said bed and having a tool-mandrel at each end thereof.

15. A universal woodworking - machine comprising a frame having a vertical faced plate, a tool-shaft bed adapted to be adjusted in vertical and horizontal positions on said plate, a tool-shaft mounted therein and carrying a tool-mandrel at each end thereof, an adjustable table supported over the center of said tool-shaft and adapted to coact with one of said mandrels when said shaft is in a vertical position, and separate independently-adjustable tables supported in relation to each end of the shaft on the respective sides of said central table and coacting with the respective tools carried by the respective mandrels of said tool-shaft.

16. A universal woodworking - machine comprising a frame having a vertical faced plate, a tool-shaft bed adapted to be adjusted in vertical and horizontal positions on said plate and carrying a tool-mandrel at each end thereof, an adjustable table supported over the center of said tool-shaft and adapted to coact with one of said mandrels when said shaft is in a vertical position, separate independently-adjustable tables supported in relation to each end of the shaft on the respective sides of said central table and coacting with the respective tools carried by the re-

spective mandrels of said tool-shaft, and a bearing-block adapted to support the outer overhanging end of one of said mandrels.

17. A universal woodworking - machine comprising a frame having a vertical faced plate, a tool-shaft bed adapted to be adjusted in vertical and horizontal positions on said plate, a tool-shaft mounted therein and carrying a tool-mandrel at each end thereof, an adjustable table supported over the center of said tool-shaft and adapted to coact with one of said mandrels when said shaft is in a vertical position, separate independently-adjustable tables supported in relation to each end 15 of the shaft on the respective sides of said central table and coacting with the respective tools carried by the respective mandrels of said tool-shaft, and a vertically-adjustable bearing-block adapted to support the outer 20 overhanging end of one of said mandrels.

18. A universal woodworking - machine comprising a frame having vertical guideways, a vertically-adjustable carriage confined in said guideways, a tool-shaft bed adapted to be supported and clamped in various 25 positions on one side of said carriage, a tool-shaft carried by said bed and having a tool-mandrel formed on each end thereof, and a separate independently-adjustable table co- 30 acting with each mandrel when the shaft is in a horizontal position.

19. A universal woodworking - machine comprising a frame having vertical guideways, a vertically-adjustable carriage confined in said guideways, a tool - shaft bed adapted to be supported and clamped in various 35 positions on one side of said carriage, a tool-shaft carried by said bed and having a tool-mandrel formed on each end thereof, a separate independently-adjustable table co- 40 acting with each mandrel when the shaft is in a horizontal position, and an outboard adjustable bearing-block adapted to support the outer end of one of said mandrels.

45 20. A universal woodworking - machine comprising a frame having guideways, a carriage vertically slidable in said guideways and having a lateral planed face, a tool-shaft bed adapted to be supported by and clamped 50 to said face in either vertical or horizontal position, a tool-shaft rotatably supported by said bed and having a tool-mandrel at both ends, a table pivoted at one side and located over the tool-shaft when in vertical position, 55 said table having an aperture therein and an apertured plate covering said aperture, whereby to permit the passage of the end of the shaft through the table, a vertically-adjustable table carried at one side of the central 60 table beneath the end of one of the tool-mandrels when the shaft is in horizontal position, whereby to feed work to the lower side of a tool carried by said mandrel, a pair of tables carried in the plane of the upper 65 edge of the tool carried by said mandrel and over said last-mentioned table, whereby to enable work to be fed to the upper side of

the tool, and a separate independently-adjustable table carried upon the opposite side of the central table and coacting with a tool 70 carried by the other mandrel.

21. A universal woodworking - machine comprising a frame having guideways, a carriage vertically slidable in said guideways and having a lateral planed face, a tool-shaft 75 bed adapted to be supported by and clamped to said face in either vertical or horizontal position, a tool-shaft rotatably supported by said bed and having a tool-mandrel at both ends, a table pivoted at one side and located 80 over the tool-shaft when in vertical position, said table having an aperture therein and an apertured plate covering said aperture, whereby to permit the passage of the end of the shaft through the table, a vertically-adjustable table carried at one side of the central table beneath the end of one of the tool-mandrels when the shaft is in horizontal position, whereby to feed work to the lower side of a tool carried by said mandrel, a pair 90 of tables carried in the plane of the upper edge of the tool carried by said mandrel and over said last-mentioned table, whereby to enable work to be fed to the upper side of the tool, a separate independently - adjustable table carried upon the opposite side of the central table and coacting with a tool carried by the other mandrel, and vertical 95 gage-plates having horizontal slotted tongues adapted to be adjustably clamped upon said 100 central table in position to gage the work fed to the respective mandrels.

22. In a universal woodworking-machine, the combination of a horizontal tool-shaft having a mandrel on one end thereof, a table 105 having inwardly-extending beams adapted to be adjustably supported over the outer end of the mandrel in stirrups carried by the frame of the machine so as to support work in position to be fed to a saw carried by said 110 mandrel, and guideways carried by the frame of the machine below said shaft adapted to receive and support the inwardly-projecting beams of the table so as to support said table below the end of the shaft in position to feed 115 work to a boring or facing tool carried by said mandrel.

23. A universal woodworking - machine comprising a frame having guideways, a carriage having a lateral planed face vertically 120 adjustable in said guideways, a tool-shaft bed having a coacting planed face adapted to be clamped in either vertical or horizontal position on said plate, a tool-shaft mounted in said bed and having a tool-mandrel formed at each 125 end thereof, a rotary cutter-head adapted to be carried on one of said mandrels, adjustable feed-tables carried above and below said cutter-head, a saw carried by the opposite mandrel, a work-table supported above the 130 center of said tool-shaft and carriage, a separate removable table having inwardly-projecting legs adapted to be supported in horizontal guideways in the frame at the level of

said central table, whereby to coact therewith in forming a work-table for the saw, and a horizontal longitudinally-slidable bed or carriage supported by said last-mentioned table and 5 adapted to have work clamped thereon, whereby to feed the work against the saw.

24. A universal woodworking - machine comprising a frame having guideways, a carriage having a lateral planed face vertically 10 adjustable in said guideways, a tool-shaft bed having a coacting planed face adapted to be clamped in either vertical or horizontal position on said plate, a tool-shaft mounted in said bed and having a tool mandrel formed at each 15 end thereof, a rotary cutter-head adapted to be carried on one of said mandrels, adjustable feed-tables carried above and below said cutter-head, a saw carried by the opposite mandrel, a work-table supported above the 20 center of said tool-shaft and carriage, a separate removable table having inwardly-pro-

jecting legs adapted to be supported in horizontal guideways in the frame at the level of said central table, whereby to coact therewith in forming a work-table for the saw, and a 25 horizontal longitudinally-slidable bed or carriage supported by said last-mentioned table and adapted to have work clamped thereon, whereby to feed the work against the saw, said central table having an aperture centrally thereof and an apertured cover-plate thereover, whereby one mandrel of the tool-shaft may project through the table and have a suitable tool clamped thereon for operating upon work on the central table. 30 35

In witness whereof I have hereunto set my hand in the presence of two witnesses.

LAURENT MORIN.
